UNITED STATES PATENT OFFICE.

WARREN K. LEWIS, OF NEWTON, MASSACHUSETTS, AND ALFRED A. WELLS, OF ROSELLE PARK, NEW JERSEY, ASSIGNEES TO STANDARD OIL DEVELOPMENT COMPANY, A CORPORATION OF DELAWARE.

FRACTIONATING HYDROCARBON.

No Drawing.

Application filed March 5, 1924. Serial No. 697,135.

This invention relates to the separating of hydrocarbons, and more particularly separations where much overlapping in successive distillate fractions is not desired.

5 In attempting to separate hydrocarbons, obstacles are encountered by reason of the peculiar attractional force existent between the molecules. Moreover, while in the case of alcohols, esters, etc., fractionation is concerned only with a few boiling points or constant boiling point mixtures, in the case of hydrocarbons on the other hand there are a legion of compounds of very close boiling points. In the past, hydrocarbon distillers, 10 particularly petroleum refiners, have accepted the conditions as constituting fixed limitations necessitating quite incomplete separations, even where re-distilling with the best equipment at hand.

20 In accordance with the present invention we establish working conditions such that the difference or range between the vapor pressures of the compounds concerned is increased, and then apply conditions favoring 25 selective separations. The primary principle involved may be made clear by illustrations; thus, while for instance at 248° F. n-hexane is about twelve times more volatile than n-decane, at 68° F. it is about forty-four times 30 more volatile; and for example in the case of aromatic compounds, while for instance benzol at 230° F. is about 2.3 times more volatile than toluol, at 86° F. it is about 3.2 times more volatile. In the practice of our 35 invention, we secure increased ease of separation by increasing the differences in relative volatility through lowering the operating boiling point, as far as feasible, this being accomplished by lowering the working

40 pressure, that is by application of vacuum; and the vapors which are boiled off are then subjected to a rectifying action or counter-current intermingling and washing through progressively cooler zones with condensed fractions resulting from the cooling 45 of the vapor current further along in its course. Any suitable type of apparatus can be used, for instance the vapors are passed through a plate and bell type of column, or a 50 tower having plates perforated with such size openings as to allow some accumulation of condensate on the plates for the vapors to successively bubble through, or any con-

struction allowing an adequate washing or interchange.

55 As showing the character of action occurring, the following experimental data may be noted:

A mid-continent petroleum distillate of 38.2° Bé. was fractionated in a plate and bell-cap column, and 10% cuts taken, in the first instance at atmospheric pressure and in the second instance, (using the same column with the same amount of reflux), under a pressure of around 27 mm. of mercury. 60 The respective cuts were then inspected by the usual laboratory methods, to determine their gravity and boiling range. The 10% point and 90% for each cut are given in the following table, being more accurate 65 than the initial and final.

Cut	Atmospheric					Vacuum					75
	Bé.	gr.	10%	90%	Spread	Bé.	gr.	10%	90%	Spread	
1---	48.5	347° F.	434° F.	87°	44°	48.8	340° F.	398° F.	58°	12°	
2---	45.7	330	464	74	57	47.7	386	440	54	34	
3---	44.7	407	484	77	54	44.7	406	453	47	15	
4---	43.5	430	498	68	34	43.5	438	485	47	28	80
5---	41.1	464	532	68	64	41.1	457	498	41	13	
6---	40.9	468	538	70	48	40.9	485	523	38	22	
7---	40.0	490	548	58	38	39.9	501	542	41	8	
8---	38.7	510	569	59	36	39.0	534	570	36	8	
9---	37.9	533	588	55	---	37.9	562	596	34	---	

85 As will be seen, the spread or range between the boiling point at 10% and at 90% on the cuts was less with the vacuum, likewise the overlap between the 90% point of one cut and the 10% point of the succeeding cut was less with the vacuum. In other 90 words, a much sharper fractionation is obtained.

As an illustration of the practical working of the process: A distillate of about 38° Bé. gravity taken from mid-continent petroleum 95 by ordinary refinery condensing equipment was redistilled, using a plate and bell-cap column for fractionating and under an operating pressure of around 30 mm. of mercury. Contained kerosene hydrocarbons were taken 100 off as vapors from the top of the rectifying column, while the stripped gas oil was taken off as liquid from the bottom.

By applying our invention with the stills used in primary distillation, a reduction can 105 be effected in heat consumption or in the

equipment necessary or both, and we contemplate in general, where hydrocarbons are to be fractionated, the carrying out of the separation through increasing the difference 5 in the relative volatility of the constituents to be separated. Distillation can be conducted either batchwise, the successive cuts of distillate being progressively taken as desired, from lightest on to heaviest, or in distillation 10 in a continuous battery where each unit is run to fractionate off one cut, the successively heavier distillates being furnished by the successive units in the battery.

The practicable extent of lowering of the 15 operating boiling point, or lowering of the working pressure, naturally depends in large measure upon the particular hydrocarbons being separated and the sharpness of separation desired. The operating pressure may 20 advantageously be lower in the case of heavier hydrocarbons, for example lubricating cuts for high flash and viscosity, than with

lighter hydrocarbons, but for practical results extreme degrees of vacuum are not essential, and ordinarily 375 mm. down to 250 mm. absolute is advantageous.

If desired, some steam may be introduced in the liquid in the still for agitation, but sufficient steam to decrease the vacuum should be avoided, otherwise the advantage 30 gained will be offset by the effect of the steam.

What we claim is:

The improvement in the art of separating kerosene hydrocarbons from a gas oil distillate, which comprises vaporizing the distillate and bubbling the vapors through progressively cooler zones counter-currently into washing contact with condensate produced by the cooling of the vapors further along in 40 course, while maintaining an operating pressure of around 30 mm. of mercury.
